(57) **CLAIM**

The ornamental design for a pan and dish assembly, as shown and described.

DESCRIPTION

FIG. 1 is a perspective view of a pan and dish assembly showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The dotted lines represent portions of the pan and dish assembly that form no part of the claimed design.

1 Claim, 5 Drawing Sheets
